UNITED STATES PATENT OFFICE

2,536,351

INSULATED METALLIC WINDOW

Achille G. Bureau, Forest Hills, N. Y., assignor to
 Reynolds Metals Company, Richmond, Va., a
 corporation of Delaware

Application February 5, 1946, Serial No. 645,510

1 Claim. (Cl. 189—76)

1

The object of the present invention is to provide a window construction characterized by the provision of opposed sash units which are adapted to be received one within the other with an intermediate insulation mutually separating the units, the units holding between them a window glass structure which preferably consists of two spaced glass members, the sash being adapted however for any usual type of window glass. Further characteristics of the invention are the provision of lateral extensions carried by the sash units in such manner that when the units are assembled to form a window sash vertical chambers are provided at the side for receiving sash balance devices. Also, the units for the lower sash are provided with depending flanges which are spaced when the units are assembled, thus providing supports for contact with the base of the window frame and also serving as a double weather-seal. These and other objects of the invention will be described with reference to the accompanying drawings, in which:

Fig. 1 is a view in elevation, partly broken away and showing in full and dotted lines a window construction consisting of a frame and two vertically slidable sash members embodying the invention.

Fig. 2 is an enlarged vertical section broken away horizontally at each sash area and taken centrally of the structure shown in Fig. 1.

Fig. 3 is an enlarged view showing in elevation the structure Fig. 2 from the exterior thereof.

Fig. 4 is a fragmentary horizontal section taken through the window frame and both upper and lower sash members when the latter are brought opposite to each other as to the glass areas.

Fig. 5 is a schematic prospective view showing the two units of the upper sash in position for mutual assembly.

Fig. 6 is a view similar to Fig. 5 showing the two lower sash units in position for mutual assembly.

Reference to Figs. 5 and 6 will readily show the general formation of the two sash units. Fig. 5 illustrates the sash units for the upper sash. The outer upper sash unit consists of a plane metallic member 1 having an opening for exposure of the window glass carried by said upper sash, and carried integrally by member 1 is a rearwardly projected rectangular glass frame 2. The rear unit of the said upper sash comprises a plane member 3 having an inwardly projected rectangular frame 4.

As shown in Fig. 2, the glass-holding frame 4 is proportioned to be received within the frame

2

2, although this arrangement may be reversed if desired. Also, the relative proportions of the frames 2 and 4 are such that they do not mutually contact when assembled. Disposed intermediate the members 2 and 4 is an insulation medium 5, Fig. 2; so that the two units of the sash are insulated one from the other throughout.

It will be seen that as to each of the two sash units the glass-receiving opening is bounded by what may be considered as a flange which projects inwardly from the frame 2 or 4 as the case may be. This flange as to the outer sash unit provides an abutment for the insulation medium 5 and conceals said insulation at such point. The corresponding flange for the inner sash unit serves as a rectangular back stop for the window glass and its holding medium.

In Fig. 2, I have shown a window glass structure at 6 consisting of two spaced panes held in position by a plastic medium indicated at 7, which may be ordinary putty.

Again referring to the upper sash arrangement, it will be seen that the members 1 and 3 extend laterally beyond their glass-holding frame members 2 and 4, as best shown in Fig. 4, so as to provide at each side of the sash a vertical extending chamber adapted to receive sash-balancing means. Also, the members 1 and 3 project upwardly beyond their frames 2 and 4 so as to form an upper double weather-seal. As shown in Fig. 2, these projections may coact with a U shaped spring seal member 8 held on the overhead strip of the window frame 9 by any suitable means, such as, studs 10.

The base wall of frame member 2 is extended inwardly to form a horizontal flange at 2x, Fig. 2, to hold weather-stripping such as that indicated at 10 for coaction with weather-stripping 11 carried by the lower sash.

The lower sash is generally similar to the upper sash. It consists of two units the outer unit being a plane face member 12 apertured to receive and to expose a window glass structure. Extending rearwardly and integrally with member 12 is a rectangular frame 13. The inner sash unit consists of a face member 14 apertured for exposure of the window glass and integrally carrying a rectangular frame 15 which, in the embodiment shown, fits within frame 13 with the exception of an arrangement by which the upper bar of frame 15 and an outwardly projected extension 15xx may lie over the upper bar of frame 13. To this end the vertical or side bars of frame 15 are cut away at 15x, Fig. 6. If desired frame

15 may be constructed of such area as to entirely encompass frame 13.

Member 14 may carry an inwardly projected lip 14x for manual lifting of the lower sash. In either case the frame members 15 and 13 will be proportioned to provide between them a clearance sufficient to receive an insulating medium 16. As in the case of the upper sash, unit members 12 and 14 extend laterally in respect to their glass-receiving frames to provide vertical side chambers for receiving sash-balancing means. Also, said members have depending extensions relatively to their said frames to provide a double weather-seal, which may be supplemented by a yieldable weather-strip such as shown at 16x, Fig. 2.

Any suitable window frame construction may be employed in conjunction with my sash elements, that indicated at 9 including, in the present embodiment, a parting bead 20, although other guide means may be employed. The lower sash, as in the case of the upper sash, may be provided with either single-pane or double-pane window glass held in position by any suitable means as for example the plastic 7.

It will be understood that various modifications may be made in the form and arrangement of the elements constituting the embodiment of the invention shown in the drawing, without departing from spirit of the invention, what I claim and

desire to secure by Letters Patent being as follows:

A metallic window comprising an upper and lower sash, each said sash consisting of two integral units, each unit having a plane face portion formed with an opening, and an inwardly directed generally rectangular flange, the flange of one unit being adapted to embrace the flange of the second unit, said units forming a glass-retaining frame, sealing means between the said flanges, each of said units being formed with a rectangular extension projected outwardly of said flanges.
